G. W. BEEBE.
CHECK PROTECTOR.
APPLICATION FILED JAN. 8, 1915.

1,252,536.

Patented Jan. 8, 1918.

UNITED STATES PATENT OFFICE.

GAYLORD W. BEEBE, OF CLAYTON, GEORGIA.

CHECK-PROTECTOR.

1,252,536.

Specification of Letters Patent.

Patented Jan. 8, 1918.

Application filed January 8, 1915. Serial No. 1,133.

To all whom it may concern:

Be it known that I, GAYLORD W. BEEBE, citizen of the United States, resident of Clayton, county of Rabun, State of Georgia, have invented certain new and useful Improvements in Check-Protectors, of which the following is a specification.

My invention relates to that class of machines for protecting checks, drafts, or other instruments, in which the upper and under surface of the paper is abraded or roughened by means of the coöperation of dies or similar devices having opposing faces between which the paper is fed.

15 The object of my present invention is to provide means for inking the abrading device which engages the under surface of the check or other paper to the end that the ink will be forced into the fiber of the paper from beneath and coöperate most effectually 20 with the inking devices above the paper to prevent any possible chance of the marks or characters being changed or obliterated.

25 The invention consists generally in providing a means for inking the cutting or abrading surface of the die that is mounted to engage the under surface of the paper.

In the accompanying drawings forming part of this specification,

30 Figure 1 is a plan view of a check protector embodying my invention,

Fig. 2 is a transverse view of the same,

Fig. 3 is a detail sectional view, showing the means for marking and abrading and 35 inking the upper and under surface of the check or other instrument,

Fig. 4 is a sectional view on the line $x-x$ of Fig. 3,

Fig. 5 is a detail view illustrating a modified construction of my attachment,

Fig. 6 is a detail view illustrating still another construction.

In the drawing, 2 represents the frame of the drawing, 2 represents the frame of the check protector, having a suitable cover 3, inking rolls 4 and 5, mounted above the vase, and a die member 6, horizontally mounted on a shaft 7 and bearing on its face a group of figures or characters that it is desired to impress upon the check, draft 45 or note. A slot 8 is formed under the cover 3 above the base, through which slot the check or other paper to be marked is inserted. Rods 9 and 10 are mounted at one side of the base on which a suitable shelf 11 is 50 hung to support the outer end of the check when the opposite end is thrust into the

space beneath the marking dies of the machine preparatory to its operation. 12 is a crank, operatively connected with the marking die by means of which the die is revolved to contact with and impress the paper, the face of the die having been previously inked by engagement with the rolls 4 and 5.

In addition to marking the upper surface of the check or draft, it has been found desirable to mark the underside also, and a grooved wheel 13 is therefore provided, supported by a shaft 14 and having a peripheral surface made up of a series of sharp edges 60 adapted to contact with the under surface of the check or other paper opposite the point of contact of the one above and usually below the impression of the figures or characters made in the check. This wheel 70 serves to crease and in some cases cut through the paper and mark or corrugate it to such an extent that it is practically impossible without detection to raise or make any alterations in the figures when once the 80 check or other instrument has been passed through the machine.

To supplement, however, this protective feature of abrading or creasing the underside of the paper, I provide a carrier 15, or 85 other support, mounted by a suitable set screw 16 on a bracket 17. A boss 17' is provided on the bracket 17 with which one end of the carrier 15 contacts, so that when the screw 16 is turned up, the carrier will 90 be forced toward the grooved wheel. This enables the user of the machine to adjust the set screw 16 to give proper tension to the inking pad. This carrier 15 contains an inking pad 18 which lies in the path of the 95 grooved wheel 13 or its cutting surface. As this wheel revolves, it contacts with the inking pad, and a considerable quantity of ink is gathered up by the sharp edges and when the underside of the check is creased or 100 lined to increase the difficulty of changing the figures or characters on the check, the ink on the wheel will penetrate the fiber of the abraded under surface of the paper so thoroughly that it will be impossible to make 105 any change or obliteration of the figures or characters without detection. The bottom of the carrier has an opening 15' therein for convenience in applying ink to the pad. The inking of this wheel may be accomplished in various ways, as by the inking pad described coming in contact with the 110

wheel or, as shown in Fig. 5, I may provide a bracket 19 with an inking-roll 20 mounted in position to contact with the grooved wheel and thoroughly ink the surface there-
5 of, instead of using the pad shown in Fig. 4.

I also prefer to provide a wheel 20 mounted on the shaft of the grooved wheel 13 and provided with pointed teeth projecting outwardly beyond said grooved wheel a
10 sufficient distance to contact with the ink roller 20 and revolve it when the grooved wheel is revolved.

In Fig. 6 I provide a gear 21 on the shaft of the ink roller to mesh with a similar gear
15 22 on a shaft of the grooved wheel, so that as the latter revolves, the ink roller will be revolved also and bring a fresh portion of the ink roller in contact with the grooved wheel. In place of the ink pad or roller, a
20 brush or other suitable inking device may be used for applying a thin coating of the ink to the surface of the grooved roller as it revolves, to be in turn deposited by it in the fiber of the paper that is being marked.
25 Such inking device may be mounted, as shown, or may be fastened in a suitable manner to the base of the machine. These modifications I regard, however, as so obvious that I have not thought necessary to illustrate them herein.

I claim as my invention:

1. A check protector for impressing or imprinting characters or figures on one face only of the paper and applying ink to an
35 abraded surface of the paper on the opposite side to the impressed characters, comprising printing dies to print or impress figures or characters on one face only of the paper, means for abrading or cutting the
40 surface of the paper on the reverse side of the figures or characters so formed, and means mounted to bear on the surface of said abrading means for inking the same to apply ink to the abraded surface of the
45 paper by the abrading means, said inking means being mounted to move toward or from the paper with said abrading means.

2. The combination, with the printing dies operating on one side of the paper to be
50 marked, of an abrading device operating on the opposite side of the paper, a bracket

wherein said abrading device is mounted, a carrier, a set screw for adjustably securing said carrier to said bracket, and an inking pad mounted in said carrier to engage said
55 abrading device, the adjustment of said screw increasing or decreasing the pressure of said pad on said abrading device.

3. The combination, with a bracket and a die mounted therein having means for cutting or abrading the surface of a check or other instrument, of a carrier having a pad for contacting with said die and adapted to engage a boss or projection on said bracket, and an adjusting screw passing through said
65 carrier intermediate its ends and tapped into said bracket, the movement of said screw increasing or decreasing the pressure of said pad on said die.

4. The combination, with the printing dies operating on one side of the paper to be marked, of an abrading device operating on the opposite side of the paper, a support wherein said abrading device is mounted, a carrier, and means for adjustably securing
70 it to said support, and an inking device mounted in said carrier, to engage said abrading device, the adjustment of said carrier increasing or decreasing the pressure of
75 said inking device upon said abrading device.

5. A check protector for impressing or imprinting characters or figures on one face only of the paper and applying ink to an abraded surface of the paper on the opposite
85 side to the impressed characters, comprising printing dies to print or impress figures or characters on one face only of the paper, a wheel having a peripheral surface for abrading or cutting the surface of the paper on the reverse side of the figures or characters so formed, a support for said abrading means, and an inking device contacting with the surface of the abrading wheel to apply
90 ink to the surface abraded by the wheel.

In witness whereof, I have hereunto set my hand this 28th day of December, 1914.

GAYLORD W. BEEBE.
